Primary Examiner — David G Muller*Assistant Examiner* — Nathan M Johnston(74) *Attorney, Agent, or Firm* — Norris McLoughlin, PA(57) **CLAIM**

The ornamental design for a lavatory cleaning device handle, as shown and described.

DESCRIPTION

FIG. 1 is a front perspective view of the lavatory cleaning device handle showing my new design;

FIG. 2 is a front side elevational view thereof;

FIG. 3 is a rear elevation view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 4 Drawing Sheets(56)
